UNITED STATES PATENT OFFICE.

WILLIAM E. CLARKE, OF ST. LOUIS, MISSOURI.

CLEANING COMPOUND.

SPECIFICATION forming part of Letters Patent No. 289,621, dated December 4, 1883.
Application filed August 18, 1883. (No specimens.)

To all whom it may concern:

Be it known that I, WILLIAM E. CLARKE, a citizen of the United States of America, residing at St. Louis, in the county of St. Louis and State of Missouri, have invented 5 certain new and useful Improvements in Cleaning Compounds; and I do hereby declare the following to be a full, clear, and exact description of the invention, such as will enable others skilled in the art to which it appertains to make and use the same.

This invention relates to certain new and useful improvements in compounds for removing stains, either from fabrics, furniture, laces, 15 feathers, kid gloves, and all such articles or materials as will be injured by water; and it is intended for cleaning such articles. It also removes grease from the aforesaid materials, and it is designed more especially as an improvement upon Letters Patent dated May 2, 20 1882, and numbered 257,381.

In my composition I employ several of the ingredients named in said Letters Patent, but with the addition of other ingredients and in 25 different proportions. I also dispense with some of the ingredients named in said patent, and by doing so produce a compound which is more effective and cheaper to manufacture.

My composition consists of the following ingredients, combined in the proportions stated, 30 namely: to six ounces of sulphuric ether, four

ounces of alcohol, one-eighth of an ounce of salts of tartar, one-eighth of an ounce of oil of cloves, one ounce of pulverized borax, one-sixth of a dram of ammonia salts, and one gallon of deodorized or refined gasoline.

The above-named ingredients are thoroughly mixed, and are applied the same as other analogous cleansing compositions.

One way of using the composition is to pour 40 the same upon a rag or sponge and rub the article to be cleaned with the aforesaid rag or sponge.

This improved composition may be used upon the finest fabrics, and will not affect their 45 color or injure the same.

Having thus described my invention, what I claim as new, and desire to secure by Letters Patent, is—

The herein-described cleansing compound, 50 consisting of sulphuric ether, alcohol, salts of tartar, oil of cloves, pulverized borax, ammonia salts, and deodorized gasoline, in about the proportions herein specified, and for the purposes set forth.

In testimony whereof I affix my signature in presence of two witnesses.

WILLIAM E. CLARKE.

Witnesses:

D. DALZELL,
F. W. STOCKTON.
